UNITED STATES PATENT OFFICE.

JAMES BURGESS DARGAVEL, OF ST. PAUL, MINNESOTA.

SCHEDULE INDICATOR.

Application filed September 22, 1925. Serial No. 57,873.

My invention relates to schedule indicators and has for its object to provide a device adapted to be used in conjunction with a timepiece for the purpose of indicating the occurrence of reoccurring events, such as the arrival or departure of street cars, trains, busses and the like.

Another object of the invention resides in providing a structure constructed so as to be readily attached to an existing timepiece with detachable designators mounted thereon adapted to be positioned adjacent the minute graduations of the timepiece so as to designate the times at which the events occur.

A still further object resides in providing an annular back having a central opening, which back is arranged to be attached to the timepiece so that the hands and face thereof are visible through the opening in said back and to position the detachable designators along the inner periphery of said back so that the same may be placed adjacent the minute graduations of the timepiece.

Another object resides in providing an annular supporting member in conjunction with said back for carrying additional designators to indicate the occurrence of other events.

A feature of the invention resides in providing supporting members upon the back for holding display cards or other means having data associated with the use of the invention or advertising matter inscribed thereon.

Other features of the invention reside in the detailed construction thereof as disclosed in the following drawings, description and claims.

In the drawings illustrating my invention in one form:

Fig. 1 is a front elevational view of my invention illustrating the same attached to a timepiece.

Fig. 2 is a rear view of the invention removed from the timepiece.

Fig. 3 is a fragmentary sectional view taken on line 3—3 of Fig. 2.

Fig. 4 is an enlarged fragmentary sectional view taken on line 4—4 of Fig. 1.

Fig. 5 is a perspective view of one of the designator bodies.

Fig. 6 is a perspective view of one of the indicating cards carried by the designator body.

Fig. 7 is a perspective view of one of the

guides used for supporting the respective data cards or advertising cards.

For the purpose of illustrating the application of my invention I have shown in Figs. 1 and 3 an ordinary timepiece A having a casing 10, shown in dotted lines in Fig. 3, a face 11, and the usual hour and minute hands 12 and 13. The casing 10 as illustrated is of rectangular shape, though it will become apparent that the device may be attached to other forms of timepieces.

The invention proper consists of a back 14 formed of sheet metal, cardboard or other suitable material which is preferably circular and is provided with a circular opening 15. The back 14 is adapted to be positioned over the face 11 of the timepiece A so that the same and the hands 12 and 13 of said timepiece are visible through the opening 15 in said back.

The invention is held supported upon the timepiece A by means of a rectangular frame 16 which fits around the exterior of the casing 10, and which is rigidly secured to the back 14, being properly positioned relative to the opening 15 so that when the device is applied to the timepiece said opening becomes centered with the face of the timepiece. This frame may be constructed of wood and the back 14 nailed or screwed to it, or the same may be of metal and soldered, welded, or riveted to the back as desired.

As before stated, the opening 15 in the back 14 is centrally located relative to the face 11 of timepiece A with the inner marginal portion 17 in close proximity to the circle on which the numerals and minute graduations of the timepiece are arranged. In conjunction with this back, I provide a number of detachable designators B which are adapted to be attached to the marginal portion 17 of back 14 and which have points 18 directed inwardly towards the numerals minute graduations and hands of the timepiece. These designators may be moved about along the marginal portion 17 and the number of such designators varied at will so as to indicate the occurrence of any number of events within the limits of the device.

In addition to the marginal portion 17 for carrying the designators B I provide an annular band 19 similar to the back 14, which is positioned behind the back 14 and has an opening 20 in it of less diameter than the opening 15 and which is concentrically arranged relative thereto so as to form an ex-

posed marginal portion 21 similar to the marginal portion 17 of back 14. This band is formed offset at 22 as illustrated in detail in Fig. 3 so as to permit of attaching the designators B to the marginal portion 17 of back 14 without interference with said band, and may be attached to the back 14 by riveting, welding, soldering, or any other suitable means. Upon this band may be placed other designators C which can be arranged in any number or position along the marginal portion 21 thereof, the same as the designators B.

The construction of the designators B and C which is identical, is clearly illustrated in Figs. 5 and 6. These devices are formed of sheet metal and comprise a body portion 23 rectangular in shape and provided with a point 24. The edges 25 and 26 of said body portion are turned over to form guides for the reception of a facing 27 shown in detail in Fig. 6, which is of the same shape as the member 23. From the body portion 23 is struck out a finger 28 which lies parallel to said body portion and in spaced relation thereto. In placing the designator upon its support, the facing 27 is slid into the guideways 25 and 26 and the entire device slipped over the marginal portion upon which it is to be mounted, said portion lying between the body 23 and the finger 28 as illustrated in detail in Fig. 4. The body 23 and finger 28 are preferably constructed of spring material so as to cause the designator to remain firmly attached. With this construction it can be readily comprehended that the designators may be mounted along either of the portions 17 or 21 in any position around the same, and that any facings 27 may be used in conjunction with them.

Together with the other features of the invention, the device is adapted to carry a number of arcuate display or advertising cards 29 which are arranged circumferentially about the face of the back 14, and in addition other display cards 30 used for giving data connected with the use of the invention or for advertising or other purposes. These cards are all held in place by means of guide bars 31 shown in detail in Fig. 7. These bars are preferably formed of sheet metal being bent over to give them an H-shaped cross section providing flanges 33 and 34 connected together to form oppositely facing grooves 35 and 36. The bars 31 are soldered or otherwise secured to the front and rear of the back 14 in radial relation so as to receive the respective cards 29 and 30, as illustrated in Figs. 1 and 2. The grooves 35 and 36 are of such dimensions as to cause the cards to become lodged therein by frictional engagement with the flanges 33 and 34. In conjunction with the advertising cards 29 I employ a number of radial pointers 38 which are formed along the inner edge of the back 14 and which lead from the central portion of each of the cards 29 and are directed towards

the hands 12 and 13. These pointers have the psychological effect of drawing the observer's attention to the advertising matter on the cards 29, when the hands 12 and 13 and said pointers come in alignment.

An exceedingly practical use to which the invention may be put is to indicate the arrival or departure of street cars, trains, or busses. When so used both sets of designators B and C are employed, each positioned upon their respective marginal portion or support 17 or 21. In this case the designators B are used to indicate the arrival of out-bound cars and designators C to indicate the arrival of inbound cars. These designators are arranged opposite the exact divisions of the hour at which the cars arrive. As the minute hand 13 moves along, the observer can readily ascertain the time he will have to wait for his car by comparing the position of the minute hand and the particular designator. Further, by observing the positions of the various designators he may ascertain the available car service. By coloring or otherwise marking the facings 27 as shown in Figs. 1 and 6, different types of service may be designated. Data tables such as illustrated at 37 explaining the use and function of the invention may be placed upon the cards 30 or 29, or elsewhere, if desired. Although I have explained the invention as used for the purposes of indicating the arrival or departure of trains, busses, street cars and the like, it can be readily understood that the invention may be used for other purposes.

The invention is particularly advantageous in that the same can be constructed at an economical cost and can be easily applied to existing timepieces without defacing or reconstructing them. The designators may be easily removed or replaced to conform with changes in service and the various types of service may be easily indicated by providing the necessary facings.

Having described my invention in the form which I consider the best embodiment thereof, I desire to have it understood that the invention may be constructed in different ways and put to uses other than those disclosed within the scope of the following claims:

1. A schedule indicator comprising a back having a circular portion, means carrying a series of graduations arranged in proximity to said portion and designating means detachably mounted upon said portion.

2. A schedule indicator comprising a back having a central opening, and forming a marginal portion, a band positioned inwardly of said opening and forming a second marginal portion, means carrying a series of graduations arranged in proximity to said marginal portions and designating

means detachably secured along both of said marginal portions.

3. A schedule indicator comprising a planiform back having a central opening, an annular member secured to said back in concentric relation with said central opening, said member being depressed along its inner margin to leave the inner margin of said back free from said member, means carrying a series of graduations arranged in proximity to the inner marginal portion of said member, designating means detachably secured along the inner marginal portion of said back, and other designating means detachably secured along the inner marginal portion of said member.

4. A schedule indicator comprising a back having a central opening, an instrument car-

rying a series of graduations in proximity to the inner marginal portion of the back, 20 said back providing a screen for that part of said instrument outside of said graduations, designating means detachably secured along the inner marginal portion of the back, guides positioned radially on said back, and sectional cards mounted between said guides and forming in conjunction therewith a continuous facing for the back, the inner ends of said guides and the inner 25 edges of said cards falling short of the inner edge of the back to provide a clear annular portion for the application of said designating means.

In testimony whereof, I have signed my name to this specification.

JAMES BURGESS DARGAVEL.
